UNITED STATES PATENT OFFICE.

JOSEPH HUNTER DICKINSON, OF LARCHMONT, NEW YORK, ASSIGNOR TO THE AEOLIAN COMPANY, A CORPORATION OF CONNECTICUT.

AUTOMATIC MUSICAL INSTRUMENT.

Application filed April 20, 1921. Serial No. 462,902.

To all whom it may concern:

Be it known that I, JOSEPH HUNTER DICKINSON, a citizen of the United States of America, residing at Larchmont, Westchester County, New York, have invented certain new and useful Improvements in Automatic Musical Instruments, of which the following is a specification.

My present invention relates to automatic musical instruments and more particularly to automatic brake-means for electric-motor driven rotary-fan suction, or wind-inducing devices. This brake automatically stops further rotation of the fan as soon as the current to the electric-motor is interrupted either manually by the operator or automatically from the tracker-board of the player-piano or similar automatic musical instrument, thereby preventing the dying-out noises from the fan which otherwise occur.

The figure in the accompanying diagrammatic drawing shows a wind inducing device embodying the present invention, the figure being a vertical cross-section partly in elevation of said device.

I will now describe my invention specifically by reference to the accompanying drawing.

1 1 is an electric-motor, having a fan 2 on its shaft 3, the whole being properly mounted within a metal casing 4, having the transverse partition 5 partially separating the fan from the space occupied by the motor.

35 The automatic action of the player piano is supposed to be connected by a tube or pipe (not shown) to the neck 6 which surrounds an opening into the motor-chamber of the device. Also the fan 2 in this particular instance is supposed to be a suction-fan arranged to exhaust the air from the automatic action by way of said neck 6 and deliver it out of the casing 4 to the atmosphere by way of the necked-opening 7 as indicated by the 45 arrows.

8 is a wheel or disc secured on the shaft 3 against which the braking action is adapted to take place.

9 is a suitably supported motor-pneumatic 50 whose movable board 9^a operates to apply or withdraw a brake-shoe 10 to the wheel 8.

11 is a light butterfly spring acting between a fixed support 12 and the movable board 9^a of the pneumatic tending to keep 55 the brake-shoe out of contact with the wheel.

13 is a valve-box having an exhaust chamber 14 separated by a diaphragm 15 from the diaphragm chamber 16. 17 is a tube connecting said chamber 14 with the motor- or suction-chamber 18 of the air-tension inducing device. 19 is a bleed-hole connecting the suction-chamber 14 with the diaphragm chamber 16.

20 is a cylindrical passage controlled by the double-valve 21—22 on the diaphragm 15. 23 is a tube and duct connection between the brake-operating pneumatic 9 and the side of the aforesaid passage 20.

24 is a tube and duct connection from the diaphragm chamber 16 to the atmosphere. 70

25 is a metal lever fulcrumed at 26 supporting a soft pad or button 27 adapted to seal the mouth of the tube 24 when the lever is in its full-line position and to open it when in its dotted position 25^a. 75

28 is a stationary metal button with which the metal lever 25 is in electrical contact when in its full-line position.

The wires 29, 30, 31 electrically connect the mains with the motor 1 by way of the 80 lever 25 and contact 28, said lever acting as a switch.

The operation is as follows: The lever 25 being in its full-line position, the electric motor 1 will be in operation and the fan 2 85 will exhaust the chamber 18 and the player action, etc., connected to said chamber by the neck 6. The valve chamber 14 will also be exhausted via the tube 17, as well as the diaphragm chamber 16 via the bleed 19. 90 Therefore, the valve 21—22 will be in their "down" position as shown, with the valve 21 shutting off the atmosphere from the passage 20 and with the valve 22 connecting the suction in chamber 14 to said passage 20, 95 tube 23 and the brake-operating pneumatic 9. In short, said motor-pneumatic 9 has substantially the same air tension upon it inside and outside, so that it is inert with the spring 11 lightly holding the brake-shoe 10 100 out of contact with the wheel 8.

The above condition persists until it is desired to stop the instrument whereupon the lever 25 is either manually or automatically swung into its dotted position 25^a. This 105 breaks the electric-motor circuit by said lever swinging away from the contact 28. Also the momentum of the motor and fan is immediately checked and further rotation stopped as follows: As soon as said lever 110

25 is moved away from the mouth of the tube 24, atmospheric air rushes into the diaphragm chamber 16, lifts the diaphragm or pouch 15, seats the valve 22 against the 5 lower port of the passage 20 and opens the valve 21, whereupon atmospheric air now rushes into said passage 20, tube 23 and motor-pneumatic 9 and forcibly expands it, carrying the shoe 10 into braking contact 10 with the wheel 8 and stopping further rotation of the motor and fan.

The suction having ceased, the atmospheric air fills the container 4 through the neck 7, whereupon, because there is now the 15 same air-pressure inside and outside the pneumatic 9, the braking action of the shoe 10 on the wheel is released, and the electric motor is free to start up again unimpeded whenever the lever 25 is swung back to its 20 full-line position.

Obviously, changes can be made in the foregoing devices in kind, form, location and the like without departing from the essence and spirit of my invention as disclosed in the foregoing specification and the 25 annexed claims, and as such, said changes are intended to be covered thereby.

What I claim is:

1. In combination with an electric-motor-driven wind-inducing device for automatic musical instruments, a brake for stopping the rotation of said device, a motor-pneumatic operatively connected to the brake and subject to opposing pneumatic pressures, 30 retracting means tending to hold the brake in non-braking position, a member controlling the supply of motive current to the electric motor of the wind-inducing device, and valve means governed according to the 35 position occupied by said controlling member

and operative, when said member is in one position, to substantially balance said pneumatic pressures acting on the motor-pneumatic and thereby permit the retracting means to hold the brake in non-braking position, and operative, when said member is in another position, to overbalance one of said pressures and thereby cause the motor-pneumatic to overcome the retracting means and 45 to actuate the brake into brake applying position.

2. In combination with an electric-motor-driven wind-inducing device for automatic musical instruments, a brake for stopping the rotation of said device, a motor-pneumatic operatively connected to the brake and 50 having its exterior exposed to the pressure existing at the suction side of said device, means for controlling the supply of motive current to the electric motor of said device, and valve means governed by said controlling means and operative, when the controlling means is in one position, to cause exhausting of air from the interior of the motor-pneumatic whereby the pressure within 55 it will substantially balance the pressure acting on the exterior thereof in consequence of which the brake will not be actuated into braking-position, and operative, when the controlling means is in another position, to admit atmospheric pressure to the interior of the motor-pneumatic whereby the pressure within 60 it will overbalance the pressure acting on the exterior thereof, in consequence of which the brake will be actuated 65 into its brake-applying position.

In testimony whereof I have signed my name to this specification this 18th day of April, 1921.

JOSEPH HUNTER DICKINSON.
